(57) CLAIM

I claim the ornamental design for a lap scarf, as shown and described.

DESCRIPTION

FIG. 1 is a perspective view of a lap scarf, showing my new design;

FIG. 2 is a top plan view thereof, the bottom plan view being a mirror image thereof;

FIG. 3 is a front elevational view thereof, the rear elevational view, left-side elevational view, and right-side elevational view all being identical thereto; and,

FIG. 4 is an enlarged fragmentary perspective view thereof.
